DESIGN FOR AN ILLUMINABLE COMPACT OR SIMILAR ARTICLE

George Zumft, Stony Brook, N. Y.

Application April 2, 1938, Serial No. 76,255

Term of patent 7 years

To all whom it may concern:

Be it known that I, George Zumft, a citizen of Germany, residing at Stony Brook, in the county of Suffolk, and State of New York, have invented a new, original, and ornamental Design for an Illuminable Compact or Similar Article, of which the following is a specification, reference being had to the accompanying drawing, forming part thereof.

In the drawing:

Fig. 1 is a bottom perspective view of an illuminable compact or similar article, showing my new design in closed position;

Fig. 2 is a top perspective view thereof in open position;

Fig. 3 is an end elevational view thereof in closed position and on a slightly smaller scale; and

Fig. 4 is a fragmentary top perspective view thereof in open position with a portion of the cover broken away for convenience of illustration.

I claim:

The ornamental design for an illuminable compact or similar article, as shown and described.

GEORGE ZUMFT.
